[57] ABSTRACT

This invention relates to a deployable blind comprising a cloth-supporting frame of adjustable width made up of a series of pivoting ribs joined by the ends of their lateral uprights and the rectilinear part of which, parallel to the pivoting axis of the said ribs, is telescopically adjustable in length; two extendable independent side cloths, fixed on each of the corresponding lateral uprights of the said ribs; and a covering cloth, rolled out from a roller, having a width substantially equal to the minimum length of the telescopically adjustable part of the ribs and independent of the side cloths which it covers at least partially regardless of the width given to the blind and being fixed only to the first of the ribs.

FIG. 4

FIG. 5

DEPLOYABLE BLIND

This invention relates to a blind which may be deployed to form an awning, of the kind generally placed over the front of a shop window, outdoor cafes or restaurants, balconies or similar places.

It is known that in this type of blind, the cloth is supported like a carriage hood by a frame made up of a series of staying ribs articulated on each other at their ends on each side of the opening.

As the dimensions of openings are not standardized, it has been necessary in the past to make each blind according to special dimensions and this represented a serious obstacle to their industrial manufacture.

The deployable blind according to the invention is designed to be mounted on such an opening and to be adapted to the width of the same.

An object of the invention concerns especially the large-scale manufacture of either complete blinds, cloth-supporting frames, or parts of such frames, which are immediately adaptable to openings of various dimensions, so that one need only manufacture a limited number of blinds or different blind elements suited to practically all dimensions of openings on which such a blind may be placed.

The deployable blind according to the invention includes :

a. A cloth-supporting frame of adjustable width made up of a series of pivoting ribs joined by the ends of their lateral uprights and the rectilinear part of which, parallel to the pivoting axis of the said ribs, is telescopically adjustable in length, the last of these ribs being held, at least indirectly, on the said opening ;

b. Two extendable independent side cloths of symmetrical form, each having sufficient dimensions to cover one of the two lateral parts of the frame when the blind is deployed as well as the corresponding ends of the rectilinear parts of the ribs and fixed on each of the corresponding lateral uprights of the said ribs ;

c. A covering cloth, rolled out from a roller mounted parallel to the upper edge of the opening, having a width substantially equal to the minimum length of the telescopically adjustable part of the ribs and independent of the side cloths which it covers at least partially regardless of the width given to the blind, this covering cloth being fixed only at its front edge to the first of the ribs and stretched freely on the other ribs on which it may slide.

According to a preferred embodiment of the invention, the lateral uprights of the ribs are joined together, pivoting, by articulation, at their ends and each have, opposite the pivoting axis of the ribs, a part having a right-angle bend terminating in a rectilinear appendage. The appendages of the two uprights of a same rib each engage telescopically in one of the two ends of a rectilinear cross-member constituting, with the said appendages, the rectilinear part of the rib whose length is telescopically adjustable.

The rectilinear cross-members, consisting of simple rectilinear sections, may, if required, be cut to the desired length or be replaced by longer ones without requiring the slightest modification in the lateral parts of the frame, in particular when the travel of the telescopic adjustment of the ribs is insufficient to give the blind the desired width.

In the preferred embodiment means are provided on each rib to block the rectilinear cross-member on the

appendages of the uprights in a desired position which depends on the width given to the blind.

The cloth-supporting frame, as a whole or in separate parts, may be stored and delivered to the installer who covers it during the installation. It is of course possible to completely prefabricate the blind, including its side cloths and its covering cloth.

According to the invention, the at least partial covering of the side cloths by the covering cloth, whatever the width given to the blind, is obtained by giving this covering a maximum width which, for each rib, is greater than the travel of the telescopic adjustment of the appendages in the rectilinear cross-member.

Advantageously the rectilinear cross-member of each rib has a rounded smooth surface, at least over the entire length of the part on which is freely stretched and allowed to slide the covering cloth.

This rectilinear cross-member is advantageously made up of a tube slotted on each end. Accordingly, said means provided for blocking this cross-member on the appendages introduced slidably, each in one of the two ends of the tube, consist of radial clamping screws each of which goes through a slot of the tube and bears on the edges of this slot with its head, on the side opposite the one on which the covering cloth is stretched.

The part of each side cloth covering the corresponding ends of the rectilinear parts of the ribs is advantageously strapped on the end of each rectilinear cross-member by a sleeve surrounding this end, traversed and fixed to the end by the means provided for blocking the cross-member on the corresponding appendage.

In order to increase the possibilities of widening of the blind, at least one of the two side cloths is advantageously provided with an extra reserve cloth folded in one or more successive folds on the corresponding ends of the rectilinear cross-members and extending perpendicular thereto.

In order to increase the advance of the blind in relation to the opening, the last of the ribs may be advantageously held indirectly on this opening by means of a cloth-covered extension with parallel ribs identical to those of the blind proper and held at mutual distances by cross-pieces, this extension also being provided with extendable side cloths and covered by the said covering cloth of the blind.

In addition, the lateral uprights may be themselves telescopically adjustable in length, side cloths of different dimensions being provided to be adapted to each of the lengths given to these uprights.

The invention together with further characteristics and advantages thereof will be furthermore better understood by reference to the following description and to the accompanying drawings in which :

FIG. 1 is an elevated view, with certain parts eliminated, of a blind according to the invention deployed to form an awning.

FIG. 2 shows similarly the same blind equipping a wider opening.

FIG. 3 is a section along III—III of FIG. 1.

FIG. 4 shows, to a greater scale, a bottom view of a part of the same blind, one of its ribs being shown in axial section.

FIG. 5 shows, in a view similar to that of FIG. 4, a blind representing a variant.

Referring to FIGS. 1, 2, 3 and 4, and according to a preferred embodiment, the deployable blind includes a cloth-supporting frame held between the sides 2 and 2a

of an opening and composed of a series of ribs pivoting approximately around a common axis 1 and joined together by articulation on each other of the ends of their lateral uprights 4 and 4a.

According to the invention, the rectilinear part of the ribs, parallel to the pivoting axis 1, is telescopically adjustable in length, so that it is possible to adapt the width of the entire cloth-supporting frame of the same blind to openings of different dimensions, in particular to a larger opening 3, 3a as shown in FIG. 2.

Each lateral upright 4 or 4a have, opposite the pivoting axis 1, a part having a right-angle bend terminating in a rectilinear appendage 6, respectively 6a. The appendages of the two uprights of a same rib each engage telescopically in one of the two ends of a rectilinear cross-member 5 which may consist of a simple rectilinear section and constitutes, with the said appendages 6 and 6a, the rectilinear part of the rib whose length is telescopically adjustable.

It will be noted that the manufacturer need only deliver to the installer, for each blind, the two lateral parts of the cloth-supporting frame, including the uprights 4, 4a and their appendages 6, respectively 6a, articulated on each other, as well as a certain number of sections of long length in which he can cut out to the desired length the cross-members 5. The covering with cloth can be carried out by the installer.

Moreover, the whole blind includes two extendable independent side cloths 7 and 7a, of symmetrical form, each having sufficient dimensions to cover one of the two lateral parts of the frame when the blind is deployed as shown in the drawings. Each side cloth is fixed on each of the corresponding lateral uprights of the ribs.

Besides, the blind includes a covering cloth 8, rolled out from a roller 9 mounted parallel to the upper edge of the opening. This covering cloth 8 has a width substantially equal to the minimum length of the telescopically adjustable part of the ribs and independent of the side cloths 7, 7a which it covers at least partially regardless of the width given to the blind. This covering cloth 8 is fixed only at its front edge to the first of the ribs and stretched freely on the other ribs on which it slides when the blind is actuated.

According to the invention, and so as to be certain that the covering cloth 8 covers at least partially the side cloths 7, 7a, for all the intermediate positions between that of the minimum spacing of the ribs, shown in FIG. 1 for the smallest opening considered 2, 2a, and that of the maximum spacing of the ribs, shown in FIG. 2 for the greatest opening 3, 3a which may be equipped with the same blind, one gives to the covering of the side cloths 7 and 7a by the covering cloth 8 a maximum width which, for each rib, is greater than the travel of the telescopic adjustment of the appendages 6 and 6a in the rectilinear cross-member 5.

The rectilinear cross-member 5 of each rib has a rounded smooth surface, at least over the entire length of the part on which is freely stretched the covering cloth 8, making it possible, during the maneuvering of the blind, for the covering cloth 8 to slide freely over all the intermediate ribs to which it is not attached.

As shown in FIG. 4, the rectilinear cross-member 5 of each rib is composed of a tube slotted at 10 on each of its two ends. The appendages 6, 6a, introduced slidably, each in one of the two ends of the tube, are secured in it by radial clamping screws 11, each going

through the slot 10 and bearing on the edges of this slot with its head, on the side of the tube opposite the one used for supporting the covering cloth 8.

One is thus certain that the head of the clamping screws 11 cannot rub against the covering cloth 8 during the maneuvering of the blind.

In FIGS. 3 and 4, the part of each side cloth 7 or 7a covering the corresponding ends of the rectilinear parts of the ribs is strapped on the end of each rectilinear cross-member 5 by a sleeve 12 surrounding this end, traversed and fixed to this end by the clamping screw 11 which blocks the cross-member 5 on the corresponding appendage 6 or 6a. One thus obtains a simple and effective attachment of these side cloths 7 and 7a on the different ribs of the cloth-supporting frame.

In the variant shown in FIG. 5, and in order to increase the possibilities of widening of the blind, at least one of the two side cloths 7 and 7a is provided with an extra reserve cloth folded at 13a in one or more successive folds 13 on the corresponding ends of the rectilinear cross-member 5 and extending perpendicular thereto. This extra cloth is fixed to the end of each cross-member 5, under the covering cloth 8, by means of flat-headed screws 14 and 15 which then are used as clamping screws for blocking the end of the cross-member 5 on its associated appendage 6 or 6a.

Although the blind according to the invention is shown, in FIG. 3, held by its last rib in the opening 2, 2a, it is possible, in order to increase its advance in relation to the opening, to hold the last of the ribs indirectly on this opening by means of a cloth-covered extension with parallel ribs identical to those of the blind proper and held at mutual distances by cross-pieces, this extension also being provided with extendable side cloths and covered by the said covering cloth 8 of the blind.

At last, the lateral uprights 4 and 4a of each rib may be themselves telescopically adjustable in length, side cloths 7, 7a of different dimensions then being provided to be adapted to each of the lengths given to these uprights.

It must be understood that the preceding description is given by way of example only and does not in any way limit the scope of the invention within which one would still remain by replacing the described embodiment details by any other equivalent.

What is claimed is :

1. A deployable blind designed to be mounted as an awning over the front of a shop window or the like and to be adapted to the width of this opening, comprising:
  - a. a cloth-supporting frame of adjustable width made up of a series of pivoting ribs joined by the ends of their lateral uprights and the rectilinear part of which parallel to the pivoting axis of the said ribs, is telescopically adjustable in length, the last of these ribs being held, at least indirectly, on the said opening;
  - b. two extendable independent side cloths of symmetrical form, each having sufficient dimensions to cover one of the two lateral parts of the frame when the blind is deployed as well as the corresponding ends of the rectilinear parts of the ribs and fixed on each of the corresponding lateral uprights;
  - c. a covering cloth, rolled out from a roller mounted parallel to the upper edge of the opening, having a width substantially equal to the minimum length of the telescopically adjustable part of the ribs and in-

dependent of the side cloths which it covers at least partially regardless of the width given to the blind, this covering cloth being fixed only at its front edge on the first of the ribs and stretched freely on the other ribs on which it may slide, the lateral uprights of the ribs being joined together pivotally, by articulation, at their ends, and wherein each have, opposite the pivoting axis of the ribs, a part having a right-angle bend terminating in a rectilinear appendage; the appendages of the two uprights of a same rib each being engaged telescopically in one of the two ends of a rectilinear cross-member constituting, with the said appendages, the rectilinear part of the rib whose length is telescopically adjustable.

2. A deployable blind as claimed in claim 1, wherein means are provided on each rib to block the rectilinear cross-member on the appendages of the uprights in a desired position which depends on the width given to the blind.

3. A deployable blind as claimed in claim 1, wherein the at least partial covering of the side cloths by the covering cloth, whatever the width given to the blind, is obtained by giving this covering a maximum width which, for each rib, is greater than the travel of the telescopic adjustment of the appendages in the rectilinear cross-member.

4. A deployable blind as claimed in claim 1, wherein the rectilinear cross-member of each rib has a rounded smooth surface, at least over the entire length of the part on which is freely stretched and allowed to slide the covering cloth.

5. A deployable blind as claimed in claim 2, wherein the rectilinear cross-member of each rib is made up of a tube slotted on each end, and in which the said means provided for blocking this cross-member on the appendages, introduced slidingly, each in one of the two ends of the tube, consist of radial clamping screws each of which goes through a slot of the tube and bears on the edges of this slot with its head, on the side opposite the one on which the covering cloth is stretched.

6. A deployable blind as claimed in claim 2, wherein the part of each side cloth covering the corresponding ends of the rectilinear parts of the ribs is strapped on the end of each rectilinear cross-member by a sleeve surrounding this end, traversed and fixed to the end by the means provided for blocking the cross-member on the corresponding appendage.

7. A deployable blind designed to be mounted as an awning over an opening such as a window or the like and to be adapted to the width of the opening comprising:

a cloth supporting frame of adjustable width, said frame comprising a plurality of ribs arranged to turn about a common axis between an open position and a folded position of the frame, each rib comprising a lateral part on each side extending radially outwardly relative to the said axis, and a rectilinear part extending between and inter-

connecting the outer ends of the said lateral parts, said rectilinear part being adjustable in width to vary the distance between its lateral parts between a maximum frame width and a minimum frame width,

a side cloth attached to the outer side of the lateral parts on each side of the frame, said side cloth extending over the radial outer ends of its respective lateral parts and extending along the rectilinear part a certain distance which is sufficient to cover the corners formed by its respective lateral parts and the rectilinear parts,

a roller mounted parallel to the said axis in the vicinity of the upper edge of the frame,

a covering cloth arranged to roll up on the said roller in the folded position of the frame and to roll out from the roller in the unfolded position, said cloth overlying said rectilinear parts and being connected only at its front edge to the rectilinear part of the outermost rib, said covering cloth being stretched freely on the other ribs on which it may slide, said cloth having a width substantially equal to the said minimum width of the frame, and said certain distance which the side cloths extend along the rectilinear parts being sufficient to at least slightly overlap the side edges of the said covering cloth closest thereto when the frame is at its said maximum width.

8. A deployable blind as claimed in claim 7, wherein, in order to increase the possibilities of widening, at least one of the two side cloths is provided with an extra reserve cloth folded in one or more successive folds on the corresponding ends of the rectilinear cross-members and extending perpendicular thereto.

9. A deployable blind as claimed in claim 1, wherein, in order to increase its advance in relation to the opening, the last of the ribs is held indirectly on this opening by means of a cloth-covered extension with parallel ribs identical to those of the blind proper and held at mutual distances by cross-pieces, this extension also being provided with extendable side cloths and covered by the said covering cloth of the blind.

10. A deployable blind as claimed in claim 1, wherein the lateral uprights are themselves telescopically adjustable in length, side cloths of different dimensions being provided to be adapted to each of the lengths given to these uprights.

11. A deployable blind as claimed in claim 7, said rectilinear parts being telescopically adjustable to vary the width of the frame.

12. A deployable blind as claimed in claim 12, the rectilinear part of each rib including a pair of outer parts, each integral with one of the lateral parts of the rib and bent from its respective lateral part along said rectilinear part, and a straight cross-member extending between and telescopically connected to the said outer parts.
